CHESTER S. JENNINGS, OF SYRACUSE, NEW YORK, ASSIGNOR TO THE LAMSON COMPANY, OF SYRACUSE, NEW YORK, A CORPORATION OF MASSACHUSETTS

PNEUMATIC CARRIER

Application filed May 17, 1929. Serial No. 363,773.

This invention relates to pneumatic despatch tube carriers and more particularly to indicating means arranged thereon, thus permitting, for example, a ready identification 5 of the station from which the carrier is transmitted or for which it is intended.

In pneumatic despatch systems it is common to provide a central station and a series of outlying stations with conveyor ducts connecting the latter with the former and for returning the carriers to the outlying stations, while analogous conditions exist in the case of more complex systems. Under such circumstances it is often desirable to provide 10 the carriers with adjustable means to afford suitable indicia to designate the receiver or the sender of the carrier. Under other conditions it is sometimes desirable to classify certain carriers in different groups, for example, for immediate and delayed attention of 15 the receiver.

The present invention provides means which may be readily applied to a standard carrier, without necessity for material alteration 20 thereof and without affecting its structural strength, capacity, or pneumatic characteristics, such means being associated with the cylindrical wall of the carrier, adapted for application at any desired point longitudinally of the carrier, and not interfering 25 with the assembly of the usual parts thereof.

The present invention more specifically provides a plurality, for example a pair of index rings which may be provided with suitable index characteristics or symbols and which may cooperate with suitable symbols 30 upon the carrier wall and which are independently rotatable to a plurality of positions respectively, whereby the various possible relations of the rings to each other and the carrier wall may afford a relatively large number of indicating combinations. Preferably the rings are positively locked against accidental rotation out of the position to which 35 they are adjusted and yet may be readily moved out of or released from their locked position without the necessity for the manipulation of extraneous locking means. Preferably the rings are arranged with a re- 40 siliently yieldable element therebetween,

which, when displaced or deformed by the movement of one of the rings toward the other, permits the first ring to be moved to a new position but prevents the second ring from being rotated as long as the first ring is 55 out of a locked position. Preferably the yieldable element may be an undulatory annular spring which is flattened by the movement of either one of the rings out of its locked position. 60

In the accompanying drawings,

Fig. 1 is an elevational view of a carrier with the improved identifying means applied thereto;

Fig. 2 is an enlarged section of one end of 65 the carrier taken along the axis of the same;

Fig. 3 is an elevational view of the carrier showing one of the rings in its released position and the undulatory spring substantially flattened; and 70

Fig. 4 is a view of the two rings, the spring therebetween and the locking elements therefor, in disassembled relation.

Referring to the accompanying drawings, and more particularly to Fig. 1 thereof, the carrier may be of any suitable type, whether the access opening be at the side or at the end, but is here shown, for example, as provided with cylindrical body portion or shell 1 and a felt head 2 at one end with the usual flexible washer 6 held in place thereby. A suitable cover 3 is secured to the other end of the carrier by a hinge 4 and normally locked in place by a fastening element 5 to afford access to the interior of the carrier. 85

In accordance with the present invention, two adjacent index rings 7 and 8 are arranged at a suitable point longitudinally of the carrier, being here shown as adjacent to one end of the carrier. An annular spring 9 is disposed between the rings. When uncom- 90 pressed, this spring is sinuous or undulatory, as shown in Figs. 4 and 1 where its sinuosity is somewhat exaggerated. The edges of the rings remote from the spring, have one or more outstanding protuberances 11 whose lateral edges preferably extend substantially at right angles to the planes of the rings. An abutment and locking member 12, preferably 95 a ring, is secured by rivets or otherwise to the 100

body of the carrier 1 adjacent to each of the rings 7 and 8. Each locking member has a plurality of rectilinear depressions or recesses 14 which are adapted to interfit with the protuberances 11 so as positively to lock the rings against rotation as long as said parts are interengaged.

Preferably the ring 8 may be provided with an annular series of index symbols which, in the present disclosure, are illustrated as numerals and which may correspond in number to the number of recesses in the corresponding locking element. The ring 7 is provided with an opening 15 which is movable into registration with any one of an annular series of symbols upon the casing to render one of the same visible when the ring is rotated to the corresponding position. Preferably the undulations of the spring 9 are so slight that it is substantially flattened by a movement of one of the rings 7 or 8 toward the other ring to an extent sufficient to release its lug 12 from locking engagement with the corresponding recess 14, as shown in Fig. 3. Accordingly the rotation of both of the rings at the same time is impossible.

If the body portion of carrier 1 is formed of metal, the rings 7 and 8 may directly engage the same, the series of symbols under the former being directly applied to the casing wall. If, as in the illustrated type of carrier, the wall of the casing is of non-metallic material such as rubber, a metal sleeve 20 may be secured by rivets 21 to the cylindrical wall of the casing, said sleeve having an annular flange 22 disposed between the end of this cylindrical portion and the washer 6. It is evident, however, that even when the sleeve 20 is employed, the dimensions of the carrier, both diametric and longitudinal, are not appreciably increased, the capacity of the carrier is not decreased, the sturdiness of connection between the carrier head and body portion is not adversely affected, and the index device, being independent of the carrier head, may be located wherever desired.

In the use of a device of this character, the ring 7 ordinarily may be rotated so that the opening 15 exposes the selected symbol and then has its protuberant portion or portions 11 engaged with corresponding recesses 14 of the adjoining locking element 12 to hold the ring in that position. Thereupon the ring 8 may be moved axially toward the ring 7 to permit the rotation of ring 8 so as to bring the desired symbol thereon into a position beside the symbol exposed by the opening upon ring 7. Thus in the position of the element shown in Fig. 1, the symbol 7 is visible through the opening 15, and the symbol 0 is disposed adjoining the same due to the positioning of the ring 8.

It accordingly is evident that I have provided a simple means for providing a large

number of possible combinations of identifying symbols for a carrier of the type disclosed. The indicating means is compact, being disposed at one end of the carrier and not increasing the effective diameter thereof or increasing its length. Neither does the application of such identifying means to a carrier require a material change in its construction. The identifying means is particularly convenient to adjust since the rings are movable in opposite directions in order to be released and rotated to a new position and since accidental rotation of one ring while the other ring is being adjusted is impossible. While I prefer to use the positive locking means provided by the interengaging teeth 11 and recesses 14, I contemplate that the present arrangement of a spring interposed between adjacent index rings may also be useful independently of the use of such positive locking elements, and regard such use as within the scope of the invention.

I claim:

1. A pneumatic despatch carrier comprising a body portion, a pair of rotary index rings carried by said body portion, resiliently yieldable means interposed between said rings and urging them oppositely in an axial direction, and abutment elements engaging the respective rings to limit such axial movement.

2. A pneumatic despatch carrier comprising a cylindrical shell, a pair of rotary index rings encircling the shell, a sinuous spring interposed between said rings and urging them oppositely in an axial direction, and an abutment element normally engaging each ring to limit such axial movement.

3. A pneumatic despatch carrier comprising a body portion, a pair of rotary index rings carried thereby, an undulatory annular spring coaxial with said rings and interposed between them, said spring urging the rings oppositely, and a fixed abutment ring normally engaging each index ring to limit the movement of the latter.

4. A pneumatic despatch carrier comprising a cylindrical body portion, a pair of rotatable index rings mounted upon the body portion, retaining means normally engaging the remote edges of the respective rings to prevent rotation thereof, and a compression spring interposed between the rings urging them axially in opposite directions into engagement with the respective retaining means, the maximum axial movement permitted by the compression spring being sufficient to permit but one ring at a time to be disengaged from its retaining means.

5. A carrier for pneumatic despatch systems comprising a casing, a pair of annular index rings thereon, said rings being rotatable about the carrier to any of a plurality of indicating positions, resilient means between the rings, and abutment elements upon

the casing having portions with which the edges of the rings are normally held in interfitting engagement, the movement of either of the rings from said interfitting engagement permitting its rotation to a new indicating position.

6. A carrier for pneumatic despatch systems comprising a casing, a pair of annular index rings thereon, said rings being rotatable about the carrier to any of a plurality of indicating positions, resilient means between the rings urging them in an axial direction, and abutment elements upon the casing, said elements and rings having protuberances and recesses normally held in interfitting engagement positively to lock the rings against rotation, the axial movement of one of the rings toward the other serving to disengage it from its locking element and permitting its rotation to a new indicating position.

7. A carrier for pneumatic despatch systems comprising a casing, a pair of annular index rings thereon, said rings being rotatable about the carrier to a plurality of indicating positions, resilient means between the rings tending to move them axially in opposite directions, and abutment elements upon the casing, said elements and rings having protuberances and recesses normally held by the action of the spring in interfitting engagement positively to lock the rings against rotation, the axial movement of one ring toward the other compressing the spring and serving to disengage the locking elements of said axially moved ring so as to permit its rotation of a new indicating position, the resilient means having a limited compressibility so that both of the rings can not be rotated at the same time.

8. A carrier for pneumatic despatch systems comprising a casing, a pair of indicating rings thereon, abutment elements upon the casing adjoining the remote edges respectively of the rings, said elements and rings having complementary interfitting protuberances and recesses normally positively locking the rings against rotation, an annular spring of normally undulatory form between the edges of the rings normally urging them axially into locked position, the movement of one of the rings axially toward the other flattening the spring until the ring is released from locked position.

9. A carrier for pneumatic despatch systems comprising a casing, a pair of indicating rings thereon, fixed abutment elements upon the casing adjoining the remote edges respectively of the rings, said elements and rings having protuberances and recesses positively locking the rings against rotation when in interfitting engagement, an annular spring between the edges of the rings normally holding them in locked position, the movement of one of the springs toward the other tending to flatten the spring and

release that ring, an annular series of symbols on the casing under one of the rings, that ring having an opening to make one of the symbols visible, the other ring having a plurality of symbols movable into axial alignment with that opening, the release of one ring from its locked position flattening the spring so that the other ring is held against release until the first ring is locked, the resulting limitation of ring movement preventing the opening from being moved out of registration with the annular series of symbols.

10. A pneumatic despatch carrier having a cylindrical shell, an index ring encircling the shell, said ring being axially movable, a fixed abutment at one side of the ring for limiting axial movement of the ring, means at the other side of the ring constituting a spring abutment, and a spring mounted upon the carrier shell between said ring and the spring abutment, said spring normally urging the ring toward said fixed abutment.

11. A pneumatic despatch carrier having a body, an index ring carried by the body, the ring being axially movable relatively to the body, abutment means for limiting axial movement of the ring, and a sinuous spring encircling the body and arranged to urge the ring toward the abutment.

12. A pneumatic despatch carrier comprising a head and a cylindrical body, a rotary index ring carried by the body, the ring being axially movable relatively to the carrier body, an abutment for limiting axial movement of the ring in one direction, and a spring mounted upon the cylindrical wall of the carrier body and arranged to urge the ring axially toward the abutment.

Signed by me at Syracuse, New York, this fourteenth day of May, 1929.
